D10-71. XR D 22,646 EX

DESIGN.

S. S. FREEMAN.
DRESSMAKER'S RULER.

No. 22,646.

Patented July 25, 1893.

UNITED STATES PATENT OFFICE.

SARAH S. FREEMAN, OF LOS ANGELES, CALIFORNIA.

DESIGN FOR A DRESSMAKER'S RULER.

SPECIFICATION forming part of Design No. 22,646, dated July 25, 1893.

Application filed April 12, 1893. Serial No. 470,111. Term of patent 7 years.

To all whom it may concern:

Be it known that I, SARAH S. FREEMAN, a citizen of the United States, residing at Los Angeles, in the county of Los Angeles and State of California, have invented a new and useful Design in Curved Rulers for Dressmakers' Use, of which the following is a specification.

My design consists essentially in a curved ruler widening near the center and tapering in differential curves toward one end of the ruler and also tapering toward the other end of the ruler, and also provided in one end with a curved slot or opening having its sides formed in differential curves starting from a common point and slowly diverging for a distance, and then quickly converging in differential curves to a common point.

The accompanying drawing illustrates my invention.

The figure is a front elevation of a ruler embodying my design.

A represents the ruler which is provided with the widened portion A' near its mid-

length. From the widest point the side lines a a' extend in differential curves slowly converging toward one end of the ruler, each curve having a multiple radii, such multiple radii both being arranged upon the same side of the ruler. From the widest point, the ruler also tapers toward the other end, one side C being formed in a curve and the other side C' being straight. In this widened portion is provided a curved slot D which has its side lines formed in differential curves starting from a common center D' and slowly diverging for a distance, and then quickly converging in differential curves to a common point d.

Now having described my design, what I claim as new, and desire to secure by Letters Patent, is—

The design for a dressmaker's ruler substantially as herein described and shown.

SARAH S. FREEMAN.
